INVENTOR:

John W. Culmer.

UNITED STATES PATENT OFFICE.

JOHN W. CULMER, OF CLEVELAND, OHIO, ASSIGNOR TO THE NATIONAL COMPUTING SCALE COMPANY, OF SAME PLACE.

DESIGN FOR A REVOLUBLE SCALE-BASE.

SPECIFICATION forming part of Design No. 34,203, dated March 12, 1901.

Application filed December 15, 1900. Serial No. 40,055. Term of patent 14 years.

To all whom it may concern:

Be it known that I, JOHN W. CULMER, a citizen of the United States of America, and a resident of Cleveland, in the county of Cuyahoga and State of Ohio, have invented a new, useful, and ornamental Design for a Revoluble Scale-Base, of which the following is a full, clear, and exact description, reference being had to the accompanying drawings, forming part of this specification.

In the drawings, Figure 1 is a top plan view of my design. Fig. 2 is a vertical transverse section on the line A B of Fig. 1, and Fig. 3 a vertical transverse section on the line C D of Fig. 1.

Broadly, the design consists of a plain table of approximately circular form, with approximately circular wings or projections on one side of the equatorial line C D, said projections being connected with the main body

of the table by curves at the said equatorial line C D on their front and by a straight line parallel with the said equatorial line at their rear, a circular depression or pocket g within the table and opposite to the line of the wings, and a continuous downwardly-projecting flange F, entirely surrounding the table.

The leading feature of my invention is the winged flanged table having the sunken pocket integral therewith, as in Fig. 1; and

What I claim is—

The design for a revoluble scale-base as shown and described.

In witness whereof I have hereunto set my hand, in presence of two witnesses, this 9th day of August, A. D. 1900.

JOHN W. CULMER.

Witnesses:

HARRY M. FRYE,
A. E. DU FRESNE.
